No. 878,990.

PATENTED FEB. 11, 1908.

H. B. NEWHALL.

CHAIN.

APPLICATION FILED MAR. 9, 1907.

UNITED STATES PATENT OFFICE.

HENRY B. NEWHALL, OF PLAINFIELD, NEW JERSEY.

CHAIN.

No. 878,990.

Specification of Letters Patent.

Patented Feb. 11, 1908.

Application filed March 9, 1907. Serial No. 361,475.

To all whom it may concern:

Be it known that I, HENRY B. NEWHALL, a citizen of the United States, and resident of Plainfield, in the county of Union and State 5 of New Jersey, have invented certain new and useful Improvements in Chains, of which the following is a specification, reference being had to the drawing accompanying and forming a part of the same.

This invention relates to chains, and more particularly, those adapted to resist heavy strains, such, for instance, as loading chains.

In the accompanying drawings showing an illustrative embodiment of this invention, in 15 which the same reference numeral shows similar parts in the several figures, Figure 1 is a side elevation of my improved chain, one of the links being shown in section. Fig. 2 is a perspective view of the square stock from 20 which the links of the chain are made. Fig. 3 is a cross-section on the line 3—3 of Fig. 1. Fig. 4 is a side elevation of my chain similar to Fig. 1 after it has been in a testing machine graphically illustrating the resisting capacity 25 of the chain.

In the illustrative embodiments of this invention shown in the drawing, 1 is the substantially square or rectangular stock from which the links 2, 2 are made. The stock is 30 fed to a chain making machine in the ordinary way and is scarfed at the ends 3, 3 and welded as shown at 4 or the chain may be made by hand.

It is well known in the art of chain making 35 that substantially square stock, for the same diameter is stronger than round stock of equal diameter. To get a chain whose links will be of the maximum strength for the minimum cross-section of stock I use as 40 previously noted substantially square stock 1 and after the ends of a link have been welded I round the welded end 5 of the link, but in doing so I shorten somewhat the sides 6, 6 of the link and work this surface 45 plus metal into the round welded end of the link 5, making that end of the link of greater diameter than the squared end 8. The central portion 7 of the round end 5 I preferably form of the greatest diameter and 50 taper each side 10, 10 from the central portion 7 to the square portion 9, 9 of the end 8 of the link. This enlarged rounded portion 7 containing the weld does not interfere with the working of the chain and is formed of just sufficient diameter to make this end 55 of the link of the same strength as the sub-

stantially square end, so that the capacity of the entire chain will be of the substantially square stock 1. In practice this is extremely advantageous, for by working sufficient of the metal into the round portion of the link containing the weld to bring its resisting capacity up to that of the substantially square stock, I am enabled to make a chain that will have the full resisting capacity of the square stock. The links of such a chain are homogeneous throughout, are of substantially the same resisting capacity and capable of being subjected to immense strains without breaking. Such chains made in accordance with my invention have been put in testing machines where they have been tested far beyond what they would ever be subjected to in practice, one of such chains being shown in Fig. 4, where it will be seen that such an abnormal and excessive strain was put upon the chain by the testing machine as to straighten or elongate the links 2. As shown in this figure the chain "has been drawn stiff" or given such an abnormal test as to lock the links together without breaking them, making practically a bar of the chain.

Having thus described this invention in connection with the illustrative embodiments thereof, to the details of which I do not desire to be limited, what is claimed as new and what is desired to secure by Letters Patent is set forth in the appended claims.

1. A chain having a series of welded links a portion of each link being substantially square in cross section, the welded end of each link being round in cross-section and of greater diameter than the corresponding portion of the squared end of the link to make all portions of the links of the chain of the same resisting capacity.

2. A chain having a series of welded links a portion of each link being substantially square in cross section, the welded end of each link being round in cross-section and of greater diameter than the corresponding portion of the square end of the link, the rounded end of the link tapering from its center towards each side of the link to make all portions of the links of the chain of the same resisting capacity.

3. A welded link for a chain, one portion of said link being substantially square in cross-section, the other portion of the link being substantially round in cross-section and of greater diameter than the corresponding portion of the non-circular part of the

link, to make all portions of the link of the same resisting capacity.

4. A welded link for a chain, a portion of the link being substantially rectangular in cross-section, the other portion of the link being substantially round in cross section, and a part of the rounded portion being of

greater diameter than the non-circular part of the link, to make all portions of the link of the same resisting capacity.

HENRY B. NEWHALL.
